UNITED STATES PATENT OFFICE.

NEWTON L. HALL, OF SALT LAKE CITY, UTAH.

DISCHARGE-SPOUT FOR BALL OR TUBE MILLS.

1,369,653.

Specification of Letters Patent. Patented Feb. 22, 1921.

Application filed August 2, 1920. Serial No. 400,570.

To all whom it may concern:

Be it known that I, NEWTON L. HALL, a citizen of the United States, residing at Salt Lake City, county of Salt Lake, and State of Utah, have invented certain new and useful Improvements in Discharge-Spouts for Ball or Tube Mills; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in ball tube or pebble mills, and particularly to a discharge spout to be used therewith.

The object of the invention is to provide such a spout which will permit quick and efficient discharge and which will retain within the mill, balls, broken balls, or over-size material which attempts to escape, without the use of a screen.

Briefly, the invention comprises a mill whose spout is located within the trunnion on the discharge side, said spout being provided on its inner surface with vanes or ribs preferably arranged in series, which vanes are in the form of interrupted threads or spirals. The spacing of the different vanes prevents the gradient of the load from being raised above the bottom of the spout.

Heretofore, in milling practice, it has been the custom to use a screen or grate to prevent the grinding medium and over-size from leaving the mill with the discharged product, these grates or screens being located at the discharge point and therefore subject to extreme wear from the tumbling load within the mill. The present invention entirely eliminates the necessity for such construction.

In the drawings:

Figure 1 is a longitudinal vertical section through a mill equipped with the present invention.

Fig. 2 is a similar section through the spout, showing the same on a larger scale than in Fig. 1. This section is also indicated by line 2—2 of Fig. 3.

Fig. 3 is a front end view taken from line 3—3 of Fig. 2.

Fig. 4 is a rear end view of a modified form of spout.

Fig. 5 is a vertical, longitudinal section taken on line 5—5 of Fig. 4.

Fig. 6 is a rear end view of a further modified form.

Fig. 7 is a longitudinal section taken from line 7—7 of Fig. 6.

The shell of the mill is shown at 1 and is provided with mill heads 2 and trunnions 52, the trunnions being hollow as indicated. The mill is provided with bearings 3 for the trunnions, a drive gear 9 on a head 2, head liners 4 and shell liners 5, and a feed spout 6 is mounted within one of the trunnions, this being provided with an internal screw 66 and being fed by a chute 7. A discharge spout 8 is mounted within the opposite trunnion, being bolted thereto by means of its flange 18 and bolts 19. In the forms of discharge spout shown in Figs. 1 to 5, the vanes are arranged in two series, the vanes 10, 12, 14 and 16 forming one series; and vanes 11, 13, 15 and 17 forming the other series. These vanes are preferably tilted or inclined inwardly toward the mill as shown, to provide a sort of pocket on the mill side of each vane at the base of the vane, whereby the pulp will tend to pocket, and thereby eliminate some of the wear. As wear takes place the free edges are gradually worn to present a surface more normal to the advancing material. If the vane were upright, the wear on the free edge would soon present a rounding, sloping surface, which would detract from the efficiency of the vanes. The various vanes 10 to 17 gradually increase in height, as shown, so that each successive vane tends to cause submergence of the preceding vane and thereby producing a variable classification of the load as well as making an effective obstruction to the splash of the mill, and to too rapid advance of the mill discharge. The spacing of the vanes leaves avenues between the same for the passage of the discharging material, which is the fine material.

In the form of Figs. 6 and 7, the vanes are arranged in four series, and the innermost wall tapers gradually to the inner surface of the spout. The vanes are not arranged in a continuous spiral position, but are staggered so that a succeeding vane in

the circuit picks up or engages the heavier load which has settled to the face of the spout and moves it so that it is engaged by the next vane which is ahead of its advance. 5 This action leaves no portion of the length of the spout which does not receive some action of the vanes upon the discharging pulp. In this form also, the vanes are shown of increasing height from inner to outer end, to 10 allow for different classification, as may be required. In this form the vanes 21, 22, 23, 24, 25 and 26 increase in height gradually in the order given, and are of such pitch that they will tend to move the load toward 15 the feed end of the spout to retain balls and over-size, while the vane 27 at the mouth of the spout has an opposite pitch to assist in the discharge and thereby quickly clear the outer end of the spout. The position of 20 the vane 27 in Fig. 7 may be in line with the space existing between the vane series, thereby preventing too rapid advance or discharge splash of the discharging material, or it may be in line with the vane series, but in either case its pitch is so adjusted as to facilitate clearing and discharge 25 of the load.

In operation, referring to Figs. 1 to 5, the spout revolves with the mill and as the mill 30 is loaded to the discharge point, the pulp or mill load advances through the spout to be discharged, and particularly through the avenues between the vane series. The spout revolves at a speed which allows the vanes 35 to interrupt and retard the advancing material, which effects a tumbling-over action. By reason of the pitch of the vane, this action forces anything engaged by the vane toward the mill, such as balls, broken parts, 40 and over-size. That part of the discharge which passes over the tops of the vanes continues to the discharge and particularly so when it is relieved from the vanes and joins in the unobstructed avenues between the 45 series. As the material advances, it is caught by a succeeding vane, which is in advance of the last vane which acted upon it, and another tumbling-over action results. The increasing height of the successive 50 vanes produces an increasingly retarding effect so that, as above pointed out, each succeeding vane produces a submerging action upon the previous vanes, so that different vanes act upon different depths of the 55 material, and classification results.

The operation of the form of Figs. 6 and 7 is similar, as will be apparent.

Variation of the shape and position of the vanes can be made according to specific 60 conditions. The vanes are preferably cast integral with the discharge spout, being formed with wear-resisting qualities. By reason of the position of the vanes, they are so located that they receive very little if any 65 action from the tumbling mill load; also

the different parts, particularly the vanes of increasing height, are so located that each successive part affects the preceding action of the mill.

From the foregoing it will be seen that I 70 have provided a device which will permit of the quick discharge of the load and at the same time retain and return to the mill balls or parts or over-size which would otherwise escape. At the same time the device 75 is very durable and presents a relatively open discharge. It also allows a surcharge of the mill load without materially raising the gradient of the pulp line within the mill.

I claim:

1. A mill having hollow trunnions, said trunnions being provided with a series of separated internal vanes, said vanes being arranged to act in planes normal to the direction of discharge flow from the mill, so that as said vanes revolve with the mill, they intermittently intercept the mill discharge to return the heavy material to the mill and allow the fines and light material 90 to discharge.

2. A mill having rotary hollow trunnions, said trunnions being provided with a plurality of internal vanes, the ends of said vanes being arranged to act in planes normal to the direction of discharge from the mill, so that as said vanes revolve, their ends will intermittently intercept the mill discharge to return the heavy material to the mill and allow the fines and light material to discharge from the mill.

3. A mill having hollow trunnions, and a discharge spout mounted within one of said trunnions, said spout being provided on its inner surface with a series of separated vanes, said vanes having a pitch adapted to return heavy or coarse parts to the mill.

4. A mill having hollow trunnions, and a discharge spout mounted within one of said trunnions, said spout being provided on its inner surface with vanes, said vanes having a pitch adapted to return heavy or coarse parts to the mill, said vanes being arranged in series with avenues between them.

5. A mill having hollow trunnions, and a discharge spout mounted within one of said trunnions, said spout being provided on its inner surface with vanes, said vanes having a pitch adapted to return heavy or coarse parts to the mill, said vanes being arranged in series with avenues between them, said vanes increasing gradually in height from the feed end to the discharge end of the spout.

6. A mill having hollow trunnions, and a discharge spout mounted within one of said trunnions, said spout being provided on its inner surface with vanes, said vanes having a pitch adapted to return heavy or coarse parts to the mill, said vanes being inclined

toward the mill to provide pockets at their bases.

7. A mill having hollow trunnions, and a discharge spout mounted within one of said trunnions, said spout being provided on its inner surface with vanes, said vanes having a pitch adapted to return heavy or coarse

parts of the mill, said vanes being inclined toward the mill to provide pockets at their bases, said vanes being arranged in series 10 with avenues between them.

In testimony whereof I affix my signature.

NEWTON L. HALL.
